PRINTING MECHANISM FOR A GOLF BALL MARKER

Original Filed Aug. 27, 1930

UNITED STATES PATENT OFFICE

JOSEPH E. MCGINNESS, OF PITTSBURGH, PENNSYLVANIA

PRINTING MECHANISM FOR A GOLF BALL MARKER

Original application filed August 27, 1930, Serial No. 478,042. Divided and this application filed May 13, 1931. Serial No. 537,042.

My invention consists of an inking and printing mechanism for golf ball markers. It is incorporated with the marker and operable therewith, in which means are provided for loosely holding the ball for rotation in contact with a row of printing type, whereby to effect printing thereon with accompanying rotation of the ball.

The subject matter of this application is a division of my former application filed August 27, 1930, Serial No. 478,042.

The particular subject matter of the present improvement will be understood in connection with the following description and illustration of the complete machine.

Generally stated, the device comprises a supporting cradle or frame having a pivotally mounted ball-engaging and pressure-exerting arm, with a printing or stamping device and inking means therefor pivotally and movably connected with the holding cradle or frame for application of the printing type to the surface of the ball, as shall be more fully hereinafter described.

In the drawing, showing one preferred embodiment of the invention:

Fig. 1 is a general plan view of the device in operative position;

Fig. 2 is a view of the marker in side elevation, showing a ball in position for marking;

Fig. 3 is a transverse sectional view on the line III—III of Fig. 2;

Fig. 4 is a view similar to Fig. 2, showing the lever-actuated movement of the ball across the face of the printing device;

Fig. 5 is a longitudinal vertical sectional view through the printing device;

Fig. 6 is a detail sectional view on the line VI—VI of Fig. 5, showing the eccentric mounting for the type plate;

Fig. 7 is a similar view on the line VII—VII of Fig. 6, with the casing and type removed.

The machine as a whole consists of a supporting frame or cradle in connection with a ball holder in operative relation to a marker having printing type or the like, an upper pivotally mounted movable ball holder being pivotally mounted with and above the cradle

for retaining and pressing a ball in contact with the type, and a lower arm pivotally connected with the cradle frame and the ball holder for control of the marker.

Referring to the drawing, I use three pivotally connected members A, B and C, each being preferably divided or bifurcated, composed of a pair of side arms 2, 3 and 4 respectively, pivotally connected at their terminals by a common cross pin 5.

Member A is of generally arcuate form, the side members 2 conforming generally to the curvature of the ball D to be marked, and provided at their inner and outer portions with contacting spools 6, having oppositely located coni-form ball contacting wheels 7.

Ball holding member A is provided with a cross pin 8 at its outer end upon which the outermost spool 6 is rotatably mounted between the arms, beyond which extends the thumb terminal a having the loop members 9 and 10, for engagement by the thumb of the user.

Member B, composed of the double or bifurcated sides 3, extends at each side beyond its pivotal connection 5 and terminates in an oval-shaped grip member b having a loop rim 11 of sufficient size and arrangement to admit of the insertion of two fingers of the hand of the operator, and in adjacent relation to the thumb terminal a.

The marker containing the type against which the ball D makes contact, consists of a rectangular casing or box E within a surrounding frame 12, having a longitudinal groove 13 at each side, adjacent its top. Inwardly extending lugs or pins 14 of side arms 3 engage the grooves 13, with an outer limiting wall 15, permitting relative movement of the ball gripping members A and B with relation to the marker E, as controlled by the lugs 14 and the holding arm or frame of the marker.

The lower member C is pivotally connected by outwardly extending pins or lugs 16 of the marker engaging lugs 17 of the side arms 4, and is provided with a terminal grasping extension 18, for engagement by the fingers of the other hand of the operator.

As thus mounted, when members A and B

are in closed position, with relation to member C, as in Fig. 2, the marker is located inwardly, with the ball D in position against one end of the printing type. As members A and B are thrust upwardly and outwardly beyond member C, as in Fig. 4, the marker is retained by pins 16, being guided by lugs 14 engaging the grooves 13 of marker E which assumes varying angles while maintaining printing contact with the surface of the ball, during rotation of the latter over the type of the marker.

The marker or printer E has downwardly extending ends 19 of the upper frame portion 12, over the side and bottom edges of which engage the ends of the U-shaped sheet metal cover 20 of box form. Its upper side edges have interlocking connection, by its resilient sides, with the inwardly extending lugs 21 of the main upper frame portion 12.

Within the marker is the inking pad 22 contained within a sheet metal holder 23 and pressed upwardly from the bottom of casing 20 by a leaf spring 24, as in Fig. 5. Such inking pad is of usual construction, having a covering against which the type may be wiped for inking at each operation, or whenever desired.

The several printing type 25 are contained within a longitudinal rectangular holder 26 of box form, pivotally mounted at each end of the marker E by means of a turning stem 27 and a set screw 28 at opposite ends of the supporting casing.

Set screw 28 is mounted in the end wall of casing 26 and bears directly against the terminal type or against a filler slug 29, dependent upon the length of the name to be printed, while the turning stem 27 is fixedly mounted in the other end wall of casing 26, as by a cross pin 30.

Stem 27 is provided with a terminal knurled wheel 31, whereby the entire casing 26 and the row of type therein may be rotated to bring the type face in contact with the inking pad and then upwardly into printing position. A cover plate 32 is loosely mounted over the type holder 26, extending by ends 33 downwardly within each end 19 of the main outer casing and having adjusting connection with the eccentric 34. Such eccentric fits within a surrounding opening through ends 33 and extends from each end of casing 26 around stem 27 and screw 28.

The cover plate 32 is longitudinally slotted for clearance of the projecting ends of the type, and the plate is capable of a limited degree of outward clearance movement for rotation of the shouldered corners of the type holder 26, when it is rotated on its pivotal mounting. Likewise, the plate is retracted to normal position, just below the face of the type, by eccentric 34.

Ordinarily, in normal position, the type project slightly beyond the surface of cover

plate 32 for action against the ball surface, and upon one complete rotation of stem 27 will be wiped across the face of the inking pad 22 for fresh marking, as often as is necessary. During such rotation, the face of slotted plate 32 is moved outwardly and then inwardly by controlling action of the eccentrics.

The spring-pressed inking pad also acts to positively hold the type holder 26 in printing position by bearing against its flat bottom, as in Fig. 3.

The function of plate 32 is to provide a contact surface for the ball just slightly below the face of the type, so that as the ball slides towards the type it will ride on to the first one without abrupt or sudden engagement. Thereupon, engagement of the ball by the type effects positive rotation of the ball. Otherwise, the printing may be smeared or the ball may be damaged by the type. This feature is of special advantage especially with a short name or merely two or three initial type at the middle or either end of the holder.

As thus constructed, when member A is elevated, ball D may be then placed between the spools 6-6 with its surface resting against one end portion of the marker, as in Fig. 2.

The terminals a and b of the device being grasped by the fingers and thumb of the operator, sufficient pressure may be exerted to press the ball D firmly against the type, and vice versa, by closing leverage action of members A and B, due to the slot and lug engagement 13-14. Member B is thus pressed toward member A, with resulting reaction of the type against the ball.

Upon thrusting members A and B away from member C, as in Fig. 4, the marker E is retained by lugs 16 of members A and B acting as a carrier for the ball, whereby it is rolled across the surface of the type, the ball rotating over the type to complete the marking operation. Thereupon, member A is thrown upwardly and the ball may be removed.

The construction and operation of the device will be readily understood and appreciated by all those familiar with golf ball markers. It is comparatively simple in construction, light in weight, composed of few parts, and is continuously efficient in operation. By removing the set screw 28 the type may be readily removed from holder 26 and other type replaced, with re-tightening by the set screw, while the inking pad may be readily removed for substitution by withdrawing the cover plate 20, if necessary.

The device is very compact and it may be carried in the pocket and used for marking a large number of balls in a comparatively short space of time.

It may be variously changed in the shape

or design of its several parts by the skilled mechanic, or otherwise modified to adapt it to varying conditions of use, but all such changes are to be understood as within the scope of the following claims.

5 I claim:

1. Printing mechanism for a golf ball marker as described consisting of a rectangular casing provided with an inking pad, a type holder having a row of type, means providing for pivoting rotation of the type holder against the pad, and a slotted plate providing type clearance movably mounted on and actuated by the type holder.

10 2. Printing mechanism for a golf ball marker as described consisting of a rectangular casing provided with an inking pad, a type holder having a row of type, means providing for pivoting rotation of the type holder against the pad, a slotted plate providing type clearance mounted on the type holder, and means on the type holder engaging the slotted plate providing outward and inward movement of the plate during rotation of the

20 type holder.

25 3. Printing mechanism for a golf ball marker as described consisting of a rectangular casing provided with a resiliently mounted inking pad, a rotatable type holder having end walls provided with annular projections, a pivoting set screw extending eccentrically through one of said projections and journalled in one of the end walls of the casing, a rotating stem at the opposite end of the type holder extending eccentrically through the other annular projection and journalled in the other end wall of the casing, and a slotted covering plate having inwardly extending end portions journalled on

30 said annular projections.

35 4. Printing mechanism for a golf ball marker as described consisting of a rectangular casing provided with a removable bottom, an inking pad within the casing and a spring therefor between the pad and said bottom, an open top type holder having end walls provided with annular projections, pivoting extensions for the end walls of the type holder extending eccentrically through

40 said annular projections and journalled in the end walls of the casing, and a slotted covering plate for the casing and the type holder having inwardly extending end portions journalled on said annular projections

45 whereby the covering plate is moved outwardly for clearance of the type as they are rotated with the holder and then moved inwardly beyond the type terminals in printing position thereof.

50 60 In testimony whereof I hereunto affix my signature.

JOSEPH E. McGINNESS.
